UNITED STATES PATENT OFFICE.

PAUL DROCAR, OF TARRS, PENNSYLVANIA.

FLOATING PLATFORM FOR SHIPS.

1,121,617.

Specification of Letters Patent. Patented Dec. 22, 1914.

Application filed August 27, 1914. Serial No. 858,864.

To all whom it may concern:

Be it known that I, PAUL DROCAR, a subject of the Emperor of Austria-Hungary, residing at Tarrs, in the county of Westmoreland and State of Pennsylvania, have invented certain new and useful Improvements in Floating Platforms for Ships, of which the following is a specification.

This invention relates to certain new and useful improvements in floating platform for ships.

An object of this invention is to provide a constantly horizontal platform adapted for use upon ship-board for preventing any supported matter thereon from being affected by the wave action upon the ship.

A further object is to provide a platform suspended above a ship's deck and provided with universal joint connections whereby the weight of the platform maintains the latter horizontal regardless of the rolling and tossing of the ship itself.

A still further object is to provide a normally-horizontal floating platform adapted to support a dining table or other furniture and also chairs or seats for the passengers.

With these general objects in view and others that will appear as the nature of the invention is better understood, the same consists in the novel combination and arrangement of parts to be hereinafter more fully described, illustrated in the accompanying drawing, and set forth in the appended claims.

In the drawing forming a part of this application and to which like-designating characters refer to corresponding parts throughout the several views, Figure 1 is a perspective view of the device mounted upon a deck. Fig. 2 is a side elevation thereof. Fig. 3 is a vertical, longitudinal sectional view of one of the adjustable supporting brackets with the shaft partly broken away, and Fig. 4 is an enlarged detail view partly in section of one of the universal joint connections of the supports.

Referring more in detail to the drawings, the deck 10 is provided with a rectangular shaped broken platform 11 supported in spaced relation above the deck by means of the suspending means hereinafter set forth. Tubular posts 12 are secured to the deck as by means of bolts 13 and arranged in spaced relations suitable for the spaced positioning of the platform 11 within the space therebetween. Curved rods 14 are slidably

mounted within the posts 12, and are provided with a plurality of sockets 15 adapted to be engaged by a set screw 16 carried by the receiving post and whereby the rods 14 are adjustably positioned. The rods 14 have their upper curving ends projecting inwardly toward the diagonally opposite post, while the free ends of the said rods are provided with ball receiving sockets 17. The platform 11 is provided adjacent each corner thereof with a stub post 18 having a ball-receiving socket at head 19. Connecting bars 20 are provided for each corner of the platform, the said bars having terminal balls at their opposite ends and adapted for being retained in position within the socket 17 of the rod and the heads 19 of the said posts 18.

The construction of the ball and socket joints which are provided at each end of each of the bars 20 is illustrated in Fig. 4, it being noted that in each instance, a retaining plate 22 is provided for preventing the ball from leaving the socket, although allowing for a free universal movement therein.

A roller 23 is journaled at each corner of the platform and it being evident that the platform may freely swing upon the supporting bars, by means of the universal connections herein described, the rollers 23 will afford an anti-friction engaging surface with the adjacent post 12 in the event of an excessive tilting of the platform relatively to the deck. A table 24 may be rigidly secured to the platform, while seats or chairs 25 for the accommodation of passengers may also be supported thereby. By the vertical adjustment of the rods 14, the normal elevation of the platform above the deck may be maintained, while the equilibrium of the table and the passengers upon the platform is automatically attained by the force of gravitation.

While the forms of the invention herein shown and described are what are believed to be the preferred embodiments thereof, minor changes may be made without departing from the spirit and scope of the invention as set forth in the claims.

What I claim as new is:—

1. In a device of the class described, comprising in combination with a deck, tubular posts, rods having their lower ends provided with sockets, and vertically slidable within said posts, adjusting means carried

by said posts, and adapted for engaging the said sockets, the upper ends of said rods being inwardly curved, a platform positioned in spaced relation above the deck, stub posts 5 at each corner of the platform, and connecting bars having universal joint connections between said rods and stub posts.

2. A device of the class described, comprising tubular supporting posts, curved 10 rods adjustably mounted within said posts and having their upper curved ends inwardly positioned, a platform positioned between said posts and having its corner portion beneath the free ends of said rod, stub

posts at each corner of the platform, connecting bars, freely movable and ball and socket connections between said bars and the adjacent ends of said rod and stub posts, anti-friction rollers journaled at the corners of the said platform, and positioned adjacent the supporting posts. 15 20

In testimony whereof I affix my signature in presence of two witnesses.

PAUL DROCAR.
